UNITED STATES PATENT OFFICE.

NICHOLAS ALTMAYER, OF COGGON, IOWA.

DESIGN FOR A MATCH-SAFE.

SPECIFICATION forming part of Design No. 26,703, dated March 2, 1897.

Application filed January 20, 1897. Serial No. 619,983. Term of patent 14 years.

To all whom it may concern:

Be it known that I, NICHOLAS ALTMAYER, a citizen of the United States, residing at Coggon, in the county of Linn and State of Iowa, have invented a new and original Design for Match-Safes, of which the following is a specification.

This invention relates to a new and original design for match-safes; and it has for its object to provide a design of this character that shall be both useful and ornamental.

The leading feature of the design resides in a frusto-pyramidal base having a flat lower side, triangular end faces, and wide quadrangular side faces, the top edge of the base being the common upper side of said quadrangular faces, a horizontally-arranged oblong approximately rectangular body of a diamond shape in cross-section and disposed cornerwise to the base, with its lower corner or angle lying in a plane above and parallel with the top edge of the base, said body being formed at one side of its upper corner or angle with a longitudinal rectangular opening 7. A vertically-disposed rectangular web portion 8 lies in the space between the top edge of the base and body and is formed with a pair of inverted-heart-shaped figures 9, arranged side by side.

In the drawings, Figure 1 is a perspective view of a match-safe embodying the herein-described design. Fig. 2 is a side view thereof.

Referring to the accompanying drawings, the numeral 1 designates a frusto-pyramidal base having a flat lower side 2, triangular end faces 3, and wide quadrangular side faces 4, the top edge 5 of the base being the common upper side of said quadrangular faces. In connection with the base 1 there is arranged horizontally above the same an approximately rectangular body 6 of a diamond shape in cross-section and disposed cornerwise to the base, with its lower corner or angle lying in a plane above and parallel with the top edge of the base, said body 6 being formed at one side of its upper corner or angle with a longitudinal rectangular opening 7. A vertically-disposed rectangular web portion 8 lies in the space between the top edge of the base and body and is formed with a pair of inverted-heart-shaped figures 9, arranged side by side.

50 What I claim is—

The design for a match-safe herein shown and described.

In testimony that I claim the foregoing as my own I have hereto affixed my signature in the presence of two witnesses.

NICHOLAS ALTMAYER.
